CONTROL APPARATUS

Frank I. Williams, Hyde Park, Mass., assignor to
American Tool and Machine Company, Hyde
Park, Mass., a corporation of Massachusetts

Application March 19, 1931, Serial No. 523,765

10 Claims. (Cl. 200—35)

This invention pertains to control apparatus and relates more especially to apparatus of the type in which a clock mechanism controls the operation of two or more electrical switches, the principal object of the invention being to provide apparatus of this general type which is of simple and practical construction and which comprises a single manually movable part which is effective to predetermine the respective times at which such switches shall be actuated. One suggested utility for such control apparatus is in the automatic control of a centrifugal extractor.

Other and further objects, advantages and utilities of the invention will be made manifest in the following more detailed description and by reference to the accompanying drawings in which:

Fig. 1 is a front elevation to small scale of a timer mechanism embodying certain features of the invention;

Fig. 1^a is a fragmentary front elevation to larger scale showing certain details of the timer mechanism;

Fig. 2 is a rear elevation of the timer mechanism of Fig. 1 but to larger scale and with the back member removed;

Fig. 3 is a vertical section on the line 3—3 of Fig. 2;

Fig. 4 is a diagram illustrating one desirable arrangement of electrical connections embodied in the control apparatus; and

Figs. 5, 6, 7 and 8 are diagrammatic views illustrating the relation between the indicating devices of the timing mechanism and the switches controlled thereby.

Referring to the drawings, the numeral 1 designates the casing of the timing mechanism, said casing being supported upon a base 2 and having the front wall 3 (Fig. 3) and the removable rear wall 4. The front wall is provided with a glazed opening 5 which receives the dial 6, suitably graduated, for example, to indicate minutes, and having an opening at its center through which projects the staff or spindle 7. A knob or handle 8 is secured to the forward end of this staff and provides means whereby the staff may be turned manually, the staff constituting means for winding the spring of the clock mechanism of the timer, thereby to start its operation, and also actuating certain switch contacts as hereafter described. The staff also carries a sleeve 9 (Fig. 1^a) which is connected at its rear end to certain parts of the timing mechanism and which may be turned independently

of the staff. In front of the dial are mounted the indicator levers 10 and 11 upon the staff 7 and the sleeve 9, respectively, having the index pointers 10^a and 11^a. The index lever 10 is hereafter referred to as the main indicator or lever, and the lever 11 as the auxiliary indicator or lever. The auxiliary lever 11 is provided with a segmental member 12 (Fig. 1^a) which underlies the end of the lever 10, and this segment 11 is provided at its opposite ends with forwardly projecting ears 13 and 14 preferably furnished with screw threaded openings for reception of the adjustable abutment elements 15 and 16 respectively. These ears 13 and 14 and/or the stop elements 15 and 16, if the latter are employed, constitute abutments for limiting the relative movement of the levers 10 and 11.

The clock mechanism of the timer is contained in a case 17 (Fig. 2) secured to the back of the wall 3 of the casing, and this clock mechanism should be of any suitable type comprising for example a spring or other power storing device which is energized by turning the staff 7, such clock mechanism comprising usual escapement mechanism or governing means which determines the rate at which it shall run, it being understood that when the staff 7 is turned, for example to the right, the spring is thereby energized, and when the handle 8 is released the spring immediately starts to return the staff 7 and the sleeve to their initial positions at a predetermined speed. Since such clock mechanisms are well known in the art as illustrated for example in Patents Nos. 1,395,098, 1,493,771, and 1,705,458, it is unnecessary to describe the mechanism of this timer in further detail.

Preferably within the casing 1, I provide a signal bell 18 and also two signal elements such as electric lamps 19 and 20 disposed behind openings 21 and 22 in the front wall 3 of the casing. Such openings are preferably provided with colored bull's-eyes 23 and 24 respectively, one of said bull's-eyes being red for example, and the other of some other color, for example green, or if preferred, uncolored so as to transmit white light. The casing 1 is preferably furnished with a socket 25 for the reception of the end of a conductor cable 26 and with a second socket 27 adapted to receive a plug in the end of a cord 29 having a plug 28 which may be plugged into a suitable socket to provide electric current for actuating the lamps 19 and 20, the signal bell 18, and a solenoid 45 hereafter described.

The operation of the apparatus is substantially as follows, it being assumed that the indicator

levers 10 and 11 are substantially in the position indicated in Fig. 5. The operator grasps the handle or knob 8 of the timer device and turns it to the right, as viewed in Figs. 1 and 5. Since in the initial position an abutment member 14 (or 16) is spaced from the main indicator lever 10, the pointer 10^a is permitted to move to the right of the pointer 11^a before it engages the abutment of the lever 11. As the pointer 10^a passes the zero point of the scale the switch 56 is opened, and at the same time controlling switch 55 is closed. When the indicator 10 strikes the abutment 14 the indicator lever 11 is then pushed forwardly with the indicator lever 10 and as the pointer 11^a passes the zero of the scale the switch 57 is closed, preferably momentarily. As the indicator lever 11 is moved as described the switch 58 is also closed, thus closing a signal circuit beginning at the plug 28 and including the switch 58, the white (or green) signal lamp 20 and leading back to the plug 28. The white signal lamp is thus caused to burn. The switch 56 has already been opened as described and the signal 19 and the bell 18 remain inactive.

25 The operator may now move the handle as much farther to the right as is necessary to set the index pointers 10^a and 11^a to the desired period of operation. If it be desired to have the stop signals 18 and 19 operate for a certain period, 30 the handle is now turned to the left to carry the pointer 10^a to the left of pointer 11^a, such movement being limited for convenience by the abutment 13. The apparatus now continues to operate the indicators 10 and 11 slowly moving back 35 toward initial position. At the end of the predetermined period the index 10^a will have returned to zero and at substantially this time the switch 55 is opened. (It is to be noted that the switch 57 is at this time open having been closed 40 only momentarily). At substantially the same time the switch 55 is opened the switch 56 is closed. As the indicator lever 10 reaches the zero point before the indicator lever 11 has returned to its initial position (providing the parts 45 have been set as above described), the latter continues to move. As the index 11^a nears the zero position the switch 57 is momentarily closed but without effect since the circuit has been broken at the switch 55 and as the index 11^a reaches the 50 zero position the switch 58 is opened, breaking the circuit through all of the signals. Thus by varying the distance between the abutments 15 and 16 the period that the stop signals will operate may be varied, it being noted that these signals 55 automatically stop after a predetermined time so that waste of current is avoided.

While I have herein disclosed a desirable embodiment of the invention, it is to be understood that various changes in detail of construction 60 and specific arrangement of parts and the substitution of equivalents may be made without departing from the spirit of the invention, and while the control apparatus as here shown is of utility in connection with the centrifugal ext- 65 tractor it is not necessarily limited to such use.

I claim:

1. Control apparatus of the class described comprising a pair of indicators manually movable from initial position to an advanced position, one 70 of said indicators having spaced abutments on opposite sides of the other indicator and disposed in the path of movement of the other of said indicators and operative to limit its movements in both directions relative to the first indicator, 75 means for automatically moving one of said in-

dicators from advanced position back to initial position, interconnected electric circuits including a plurality of switches, and connections between said switches and indicators constructed and arranged to operate the switches successively 5 during the advance movement of the indicators and during the return movement again to operate the switches successively in reverse direction.

2. Control apparatus of the class described comprising a main indicator manually movable 10 from an initial position to an advanced position, a second indicator having a portion movable along substantially the same path of travel as the main indicator, spaced abutments on the main indicator disposed on opposite sides of said 15 portion of the second indicator and operative to limit the movements of the second indicator in both directions relative to the main indicator, drive means for moving one of the indicators from advanced position back to initial position, a 20 plurality of electric switches, and connections between said switches and indicators constructed and arranged to operate the switches during advance movement of said indicators and reversely operate said switches during return movement 25 of said indicators.

3. Control apparatus of the class described comprising a main indicator manually movable from an initial position to an advanced position, a second indicator having a portion movable 30 along substantially the same path of travel as the main indicator, spaced abutments on the main indicator disposed on opposite sides of said portion of the second indicator and operative to limit the movements of the second indicator in 35 both directions relative to the main indicator, automatic means for returning both of said indicators back to initial position, a pair of electric switches, and connections between said switches and indicators constructed and arranged to close 40 said switches successively during advance movement of said indicators and to open said switches successively during return movement of said indicators.

4. Control apparatus of the class described 45 comprising a pair of indicators manually movable from initial position to an advanced position, one of said indicators having spaced abutments disposed on opposite sides of the other of said indicators operative to limit the movements of the 50 latter in both directions relative to the former, drive means for returning said indicators from an advanced position back to initial position, a plurality of double acting electric switches, and connections between said switches and indicators 55 constructed and arranged to operate said switches successively in one direction during advance movement of said indicators and to operate said switches successively in reverse direction during 60 return movement of said indicators.

5. Control apparatus of the class described comprising a main indicator, a second indicator, the main indicator having spaced lugs disposed on opposite sides of the second indicator operative to limit the movement of said indicators in both 65 directions relative to each other to a predetermined range, a handle for manually moving one of the indicators in either direction thereby to move the other indicator to a selected set position after a predetermined movement of the first 70 indicator, the latter thereafter being movable relative to the other indicator within a predetermined range in the reverse direction, an electric switch control member actuatable in response to movement of each indicator, and means for mov- 75

ing said indicators back to their initial position at a predetermined rate of speed.

6. Control apparatus of the class described comprising a main indicator, a second indicator, the main indicator having spaced lugs disposed on opposite sides of the second indicator operative to limit the movement of said indicators in both directions relative to each other to a predetermined range, a handle for manually moving one of the indicators in either direction thereby to move the other indicator to a selected set position after a predetermined movement of the first indicator, the latter thereafter being movable relative to the other indicator within a predetermined range in the reverse direction, means for moving said indicators back to their initial position at a predetermined rate of speed, interconnected electric circuits including a pair of switches, and connections between said switches and indicators operative successively to close certain of said switches during advance movement of said indicators and during reverse movement to open the first closed switch after a predetermined period of time and then the last closed switch at a predetermined later time.

7. Control apparatus of the class described comprising a main indicator, a second indicator, the main indicator having spaced lugs disposed on opposite sides of the second indicator operative to limit the movement of said indicators in both directions relative to each other to a predetermined range, a handle for manually moving one of the indicators in either direction thereby to move the other indicator to a selected set position after a predetermined movement of the first indicator, the latter thereafter being movable relative to the other indicator within a predetermined range in the reverse direction, means for moving said indicators back to their initial positions at a predetermined rate of speed, interconnected electric circuits including a plurality of switches, and connections between said switches and indicators constructed and arranged to close certain of said switches and open others during advance movement of said indicators and during reverse movement to open the closed switches and close the open switches, thereby to produce coordinated effects in said circuits.

8. Control apparatus comprising a main indicator manually movable from an initial position to an advanced position, an auxiliary indicator, the main indicator having spaced abutment mem-

bers disposed on opposite sides of the auxiliary indicator, one of said abutment members being engageable with said auxiliary indicator after the main indicator has been advanced a predetermined distance from its initial position, thereby to advance said auxiliary indicator in response to further advance movement of said main indicator, the other of said abutment members being engageable with said auxiliary indicator after the main indicator has returned a predetermined distance from its advanced position, thereby to return said auxiliary indicator in response to further return movement of said main indicator, means for automatically moving said main indicator back to initial position at a predetermined rate of speed, and electrical switches having parts constructed and arranged to operate the switches successively during the advance movement of each indicator and which again operate the switches in succession during the return movement of said indicators.

9. Controlling apparatus comprising switches, a clock mechanism, a main indicator for determining the time of operation of one switch, an auxiliary indicator for determining the time of operation of another switch, the main indicator being movable to either side of the auxiliary indicator, lugs projecting from the auxiliary indicator into the path of the main indicator for limiting relative movement of the indicators, the movement of the main indicator in a predetermined direction starting the clock mechanism into action, setting the clock mechanism for a predetermined period of operation and closing a switch, said movement also moving the auxiliary indicator thereby to close another switch, the clock mechanism being constructed and arranged upon release of the main indicator to begin a slow return movement of both indicators toward normal position.

10. Control apparatus of the class described comprising a plurality of electrical switches, an actuating element for each switch, a single control member for moving said actuating elements in a given direction for first operating one of said switches and then another, and automatic means for moving said actuating elements in the reverse direction whereby to operate the first actuated switch after a predetermined period of time and to operate the last actuated switch at a predetermined later time.

FRANK I. WILLIAMS.
